SHOE

Amos Madson, Pontiac, Ill., assignor, by mesne assignments, to Double Stitch Welt Shoe Corporation of Delaware

Application July 15, 1920, Serial No. 396,607

9 Claims. (Cl. 36—16)

This invention relates to shoes and more particularly to the construction of the same by securing together the upper and the sole or bottom.

One of the objects of this invention is to provide a shoe in which the upper is secured to the sole or bottom in such a manner as to provide a shoe of great strength adapted to keep its shape and which is comfortable to the foot.

Another object is to provide a shoe in which the seam securing the upper to the sole or bottom is arranged in such a manner as to be covered in order to present a neat appearance and a smooth inner foot-supporting surface.

Another object is to provide a shoe in which the upper is secured to the sole or bottom at the forepart and heel in such a manner as to secure maximum strength while maintaining a neat appearance.

Another object is to provide methods of making shoes which will accomplish the above objects so as to cheapen the manufacture and permit ready repair thereof.

Further objects will appear from the detail description taken in connection with the accompanying drawing, in which:

Figure 1 is a detail section through the forepart of a shoe illustrating a stitch-down shoe embodying this invention;

Figure 2 is a view similar to Figure 1, but illustrating another form of shoe employing a welt and embodying this invention;

Figure 3 is a view of the bottom of the heel seat before application of the lift and outsole;

Figure 4 is a side elevation of Figure 3 but showing part in section;

Figure 5 is a view similar to Figure 3 but showing the outsole and lift in place, part of the lift being broken away;

Figure 6 is a side elevation of Figure 5 and showing the heel in place;

Figure 7 is a cross sectional view taken along line A—A of Figure 5 and showing the lift in place; and

Figure 8 is a sectional view taken along line B—B of Figure 5 and showing the heel in place with the parts in the position assumed after the heel is subjected to the usual pounding operation.

Generally stated and in accordance with this invention, the shoe comprises an insole which has a heel portion of reduced width providing a marginal recess along the heel and which has a marginal extension of reduced thickness along the forepart providing a shoulder therealong. An upper is lasted and seamed against this shoulder along the forepart, while the heel part

of the upper is lasted inwardly into and co-extensive with the marginal recess and secured in such lasted position; an outsole is also secured to this insole. In this specification and the claims the term "forepart" is used in the sense of including the shank, as well as the ball and toe of the sole, that is the entire position forwardly of the heel breast. In accordance with an embodiment of this invention a welt is laid along the marginal extension along the forepart and the outsole is seamed to the welt and the marginal extension; this welt may either overlie the out-turned margin of the upper overlying the marginal extension, or the upper may be trimmed off where it is seamed to the insole so that the welt will directly engage the marginal extension. The marginal extension of reduced thickness may be formed by channeling or slitting the insole and this may provide either a shoulder therealong or an upwardly extending inside lip arranged to lie against the inside of the upper. The inseam connecting the upper, and the welt if employed, with the insole preferably lies within a channel in the outside face of the insole so that the inseam will lie within the insole in order to leave the outside face of the insole flat, and the outsole lies against this flat face of the insole. While the heel portion of reduced width provides a marginal recess along the heel into which the upper is lasted at the heel seat, the outsole may also be marginally reduced at the heel so as to provide a similar marginal recess along the heel into which the upper may be lasted and secured in lasted position. A lift is generally provided at the heel connecting with the ends of the marginal extension on the insole; where a welt is employed this lift also connects with the ends of the welt, and where the outsole is marginally reduced the lift also connects with the ends of the marginal extension on the outsole. Both the lift and the parts to be connected may be beveled and the seam may run into this lift so as to form a neat joint.

Referring to Figure 1, 1 designates an insole which is slit or channeled at its edge to provide an upstanding lip 2 and a marginal extension or feather 3 so as to provide a shoulder 4 at the junctions of the lip and extension. This insole is also provided on its outside face with a channel 5 for receiving the inseam which lies within the insole so as to leave the outside face of the insole flat. The upper 6 and the lining 7 are secured at the shoulder 4 by a seam 8 passing through the upper and lining inwardly and downwardly through the insole and in the channel 5. 110

The outer edge or margin of the upper is turned out over the marginal extension along the entire forepart as shown at 9 and on this out-turned edge may be placed a welt 10. The outsole 11 is secured to the shoe by a seam 12 passing through the welt, upper, marginal extension and outsole.

In practice the upper (including the lining) is lasted over the insole in any suitable manner and secured against the shoulder 4 by the inseam 8, 10 the channel lip being turned at this time as is usual in the application of inseams. This channel is then cemented down and the marginal edge of the upper is turned over the marginal extension and cemented down, the lining being 15 trimmed shorter than the out-turned part of the upper. The outsole is later applied to the insole and secured by the seam 12 at the same time that the welt is applied which may be accomplished by any suitable machine. It will be noted 20 that the upstanding lip 2 is beveled so as to lie against the lining and in fact really merges therewith.

In the embodiment shown in Figure 2, the upstanding lip 2 is omitted and the shoulder 4 is undercut so as to provide a marginal groove 25 extending around the sole. A welt 10, in this case, is secured at its upper edge by the inseam 8 which also secures the upper and the lining to the insole, the outer edge of the welt being turned up during such inseaming operation as shown 30 in dotted lines, Figure 2. The welt is later turned over the marginal extension 3 and secured with the latter to the outsole by the seam 12.

It will, therefore, be seen that in the embodiments Figures 1 and 2, there are provided strong 35 seams between the upper and insole, while the insole itself as well as the upper and lining are partly attached thereto or securely fastened by the outseam to the outsole. This avoids the objectionable space between the outsole and insole 40 usually present in welt shoes and, therefore, provides a shoe which will keep its shape. The inside of the shoe is entirely smooth and free from all seams whatsoever thereby having the advantage of the welt shoe as to smooth interior and 45 shapeliness and of the McKay shoe as to strength of seam.

Referring to Figures 5 and 8 which show the heel seat construction, while as previously described, the upper along the forepart is secured 50 against an outside shoulder along the marginal extension, and, as shown in Figure 1, with the upper turned outwardly, and, as shown in Figure 2, with the welt lying along the marginal extension; at the heel part the upper, including 55 its lining and the counter, where employed, are lasted inwardly into and co-extensive with the marginal recess at the heel. As particularly shown in Figures 3 and 4, the heel portion 50 of 60 reduced width, and providing a marginal recess 34 therealong and shoulders 35 at the breast, has the lining and also the counter 38, where employed, lasted inwardly and secured in lasted 65 position as by tacks 39. Where the outsole is also marginally reduced at the heel part so as to provide shoulders 36, similar to the shoulders 35 70 on the insole, the upper 6 may be lasted inwardly over the marginally reduced part 51 and secured by tacks 40. A lift 41 may then be placed over the heel seat and secured by tacks 42. The lift 75 is beveled, as shown at 37, with a corresponding bevel or bevels on the welt, upper, insole and outsole at the shoulders 35 and 36 and the seam 12 connecting the layers of material along the forepart is extended into the lift at 43. It will be

understood, of course, that the parts 50 and 51 may be reduced in thickness. The heel is shown at 44.

Figure 8 is a sectional view illustrating the layers of material in a distinctive manner and with the thicknesses of the layers substantial in order to show their relation. In the position shown in this figure, the parts have already been subjected to the usual pounding operation familiar to those in the art, by which the various layers are caused to conform to one another.

The procedure in making the shoe may be performed by the usual machinery as now employed in shoe factories. In the specific shoe shown the procedure may be as follows:—The upper and lining are cut and stitched as usual and the soles die out in any suitable manner. The insole is slit or channeled and the lip 2, where employed, turned up, while the reduced ends of the sole or soles may be beveled as shown. The insole is then placed on the last and the upper (including the lining where employed) is lasted against the shoulder 4 along the forepart and seamed to the insole and against the shoulder. Where a welt is employed as in Figure 2, it is seamed to the sole 100 during the inseaming operation and the upper and lining are turned as shown. The lining and counter are lasted over the heel seat and secured as shown in Figures 3 and 4. The outsole is laid and where the upper is lasted over a marginally 105 reduced part of the outsole it can be secured as shown in Figures 5 and 8. The lift can now be placed over the heel seat and fitted to join the ends of the out-turned upper, the shoulders 35 on the insole and even the shoulder 36 on the 110 outsole. The outsole can now be seamed to the insole; where the welt is as shown in Figure 1, the welt is secured by the seam 12 as shown; where the welt is as in Figure 2, it is turned down on the marginal extension and secured by the 115 seam 12; in both cases the ends of the welt are fitted to the lift and the seam is run for short distances into the lift. The heel can now be applied in any suitable manner.

It will, therefore, be seen that this invention 120 accomplishes its objects. With the sole or soles formed as described, with the upper lasted along the forepart and at the heel part as described, a shoe is produced which will not only be neat 125 in appearance and strong, but in which the insole and outsole may be arranged so as to lie together while the inside of the shoe is left smooth and free of stitches or fastenings except at the heel part. The construction at the breast is particularly strong, as well as neat in that it not only 130 avoids any objectionable hump or interruption, but also securely connects the parts so as to form an integral structure having a neat appearance. The shoe may be readily resoled since the outsole may be readily removed and replaced for 135 the reason that the upper is not only connected to the insole but the connection at the heel seat can be so remade, if a complete sole is placed in position, as to again secure the advantageous construction.

Although a number of embodiments of this invention have been shown and described, it will be understood that this invention is susceptible of other embodiments and that various sub-combinations and features are of individual utility 145 without reference to other sub-combinations, combinations and features; it is, therefore, to be understood that such sub-combinations and features within the scope of the appended claims are contemplated.

Having thus described the invention, what is claimed is:

1. A shoe comprising, an insole having a heel portion of reduced width providing a marginal recess along the heel and having a marginal extension of reduced thickness along the forepart providing a shoulder therealong, an upper lasted and seamed against said shoulder along the forepart, the heel part of the upper being lasted inwardly into and coextensive with said marginal recess and secured in such lasted position, and an outsole secured to said insole. 80
- 15 2. A shoe comprising, an insole having a heel portion of reduced width providing a marginal recess along the heel and having a marginal extension of reduced thickness along the forepart providing a shoulder therealong, an upper lasted and seamed against said shoulder along the forepart, the heel part of the upper being lasted inwardly into and coextensive with said marginal recess and secured in such lasted position, a lift at the heel connecting with the ends of the marginal extension on the insole, and an outsole secured to said insole. 85
- 20 25 3. A shoe comprising, an insole having a heel portion of reduced width providing a marginal recess along the heel and having a marginal extension of reduced thickness along the forepart providing a shoulder therealong, an upper lasted and seamed against said shoulder along the forepart, the heel part of the upper being lasted inwardly into and coextensive with said marginal recess and secured in such lasted position, and an outsole seamed to and along the marginal extension on the insole. 90
- 30 35 4. A shoe comprising, an insole having a heel portion of reduced width providing a marginal recess along the heel and having a marginal extension of reduced thickness along the forepart providing a shoulder therealong, an upper lasted and seamed against said shoulder along the forepart, the heel part of the upper being lasted inwardly into and coextensive with said marginal recess and secured in such lasted position a welt along the upper and said marginal extension, and an outsole seamed to said welt and said marginal extension. 95
- 40 45 5. A shoe comprising, an insole having a heel portion of reduced width providing a marginal recess along the heel and having a marginal extension of reduced thickness along the forepart providing a shoulder therealong, an upper lasted and seamed against said shoulder along the forepart, and an outsole secured to said insole and having a heel portion of reduced width providing a marginal recess along the heel, the heel part of the upper being lasted inwardly into and coextensive with said marginal recesses and secured in such lasted position. 100
- 50 55 60 6. A shoe comprising, an insole having a heel portion of reduced width providing a marginal recess along the heel and channelled along the forepart to provide a marginal extension of reduced thickness and an inside shoulder therealong adapted to leave the outside face of the insole flat, an upper lasted and seamed against said shoulder along the forepart, the heel part of the upper being lasted inwardly into and coextensive with said marginal recess and secured in such lasted position, an outsole lying against said insole, and a seam passing through said outsole and the marginal extension on said insole. 105
7. A shoe comprising, an insole having a heel portion of reduced width providing a marginal recess along the heel and channelled along the forepart to provide a marginal extension of reduced thickness and an inside shoulder therealong adapted to leave the outside face of the insole flat, an upper lasted and seamed against said shoulder along the forepart, the heel part of the upper being lasted inwardly into and coextensive with said marginal recess and secured in such lasted position, a welt overlying said extension, an outsole lying against said insole, and a seam passing through said outsole and the marginal extension on said insole and its overlying welt. 110
8. A shoe comprising, an insole having a heel portion of reduced width providing a marginal recess along the heel and channelled along the forepart to provide a marginal extension of reduced thickness and an inside shoulder therealong, an upper lasted against said shoulder and entirely along the forepart with its margin overlying said extension, an inseam passing through said upper and insole entirely along said shoulder and lying within said insole adapted to leave the outside face of said insole flat, the heel part of the upper being lasted inwardly into and coextensive with said marginal recess and secured in such lasted position, an outsole lying against said insole, and a seam passing through said outsole and said extension and its overlying upper margin. 115
9. A shoe comprising, an insole having a heel portion of reduced width providing a marginal recess along the heel and channelled along the forepart to provide a marginal extension of reduced thickness and an inside shoulder therealong, an upper lasted against said shoulder and entirely along the forepart with its margin overlying said extension, an inseam passing through said upper and insole entirely along said shoulder and lying within said insole adapted to leave the outside face of said insole flat, the heel part of the upper being lasted inwardly into and coextensive with said marginal recess and secured in such lasted position, a welt overlying the margin of the upper along said insole extension, an outsole lying against said insole, and a seam passing through said outsole and said extension and its overlying upper margin and welt. 120
- 125 130 135

AMOS MADSON.
